UNITED STATES PATENT OFFICE

2,346,067

CIGARETTE HOLDER

Antonio Di Rubbio, Brooklyn, N. Y.

Application December 22, 1941, Serial No. 424,047

1 Claim. (Cl. 131—175)

My invention relates to improvements in cigarette holders, the principal object in view being to provide a simply constructed device of this character adapted to hold a cigarette in a manner such that cigarette smoking is rendered safe in bed, in automobiles, or in any other place in which cigarette sparks are liable to cause fires, and which may be deposited on tables, or other furniture, while the cigarette is lighted without any fire hazards or ashes falling onto the furniture.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in side elevation of the preferred embodiment of my invention,

Figure 2 is a view in longitudinal section,

Figure 3 is a view in transverse section taken on the line 3—3 of Figure 2,

Figure 4 is a similar view taken on the line 4—4 of Figure 2,

Figure 5 is a view in perspective of the butt ejector.

Figure 6 is a fragmentary view in longitudinal section of a modified form of holder.

Figure 7 is a view in side elevation of another modified embodiment of the invention.

Figure 8 is a view partly in side elevation and partly in longitudinal section taken on the line 8—8 of Figure 7.

Figure 9 is a view in transverse section taken on the line 9—9 of Figure 7 and showing the holder closed.

Figure 10 is a similar view showing the holder open, and

Figure 11 is a fragmentary view in side elevation of the inner shell of the modified embodiment shown in Figures 7 to 10.

Referring to the drawings by numerals, and first to Figures 1 to 5 thereof, my improved cigarette holder comprises a mouth bit 1 having an enlarged outer cylindrical end 2 stepped down to provide a reduced intermediate shouldered portion 3 and a further reduced shouldered outer portion 4. The portions 3 and 4 are bored axially for the insertion of one end of a cigarette 5 therein with a friction grip. A draft counter-bore extends from the first-mentioned bore 6, as at 7, to the mouth end of the bit 1.

An inner cylindrical shell 8 suitably perforated,

as at 9, and having a closed outer end 10 is fitted at its inner end over the reduced portion 4 with a friction fit. A similar larger outer shell 11 is fitted at its inner end over the reduced portion 3. As will be understood, the inner and outer shells 8, 11, are of the requisite length to accommodate the portion of a cigarette 5 extending out of the bore 6. A cylindrical nut 12 extends outwardly through the closed ends of the inner and outer shells 8, 11 into a rounded end guard 13 opposed to the closed end of the outer shell 11, said nut having a flanged inner end 14 abutting the closed end of the inner shell 8. A screw 15 is extended through the guard 13 into the nut 12 whereby said guard is detachably secured to the closed end of the outer shell 11. The outer shell is crimped substantially midway of its ends to provide a circumferential reinforcing peripheral rib 16 thereon. A pair of spacer rings 17 surround the inner shell 8 adjacent opposite ends thereof to maintain the shells 8 and 11 in concentrically spaced relation. A washer 18 on the nut 12 may be interposed between the outer ends of the inner and outer shells 8 and 11 for a purpose which will be apparent. A sleeve 19 of soft material is provided on the outer shell 11 around the inner end portion thereof for providing a comfortable hand grip.

An elongated strip-like ejector slide 20 is mounted at its inner end in the bore 6 with its outer end extending out of said bore into the inner shell 8, and it is provided with a right angled hand grip lug 20 for manipulating the same. Intermediate its ends, said slide is provided with a right angled ejector lug 21 adapted to be disposed behind the inner end of the cigarette 5. The inner end of the ejector slide is slidably mounted in a longitudinal slot 22 provided in the outer end 2 of the bit 1 and provided with a longitudinal guide slot 23 through which a pin 24 extends, said pin being inserted transversely into the outer end of the bit 1 and through said slot.

As will now be seen, the inner and outer shells 8 and 11 form guards around the cigarette 5 preventing any sparks from escaping from the holder so that the fire hazard in smoking is eliminated, while at the same time sufficient air may enter the shells to provide for proper combustion. The shells 8 and 11 may be pulled off the outer end 2 of the bit 1, as a unit, together with the sleeve 19 whenever it is desired to eject a cigarette butt from the bore 6 and insert a new cigarette. By pulling the ejector slide 20 outwardly through the medium of the

hand grip lug 20, the cigarette butt will be picked up by the ejector lug 21 and may be easily and quickly ejected from the bore 6.

In the modified form of the holder shown in Figure 6, the outer end 25 of the mouth bit 26 is provided with an internal groove 27 into which the inner end of the outer shell 28 is fitted. Otherwise the construction and arrangement is the same as described with reference to the previously described preferred form of the invention.

In the modified embodiment shown in Figures 7 to 11, the construction is the same as in the preferred embodiment with the exception that the inner and outer shells 29, 30 are provided adjacent the front ends thereof with a pair of side openings 31, 32, respectively, adapted to be registered by rotation of the outer shell 30 relative to the inner one so that the holder may be opened as shown in Figure 10 for the insertion of a match into the inner shell 29 to light a cigarette 33. Obviously, by rotating the outer shell 30 from a position in which said openings 31, 32 register the holder may be closed after the cigarette has been lit, as shown in Figure 9.

The foregoing will, it is believed, suffice to impart a clear understanding of my invention without further explanation.

Manifestly, the invention is susceptible of

modification in other respects than as herein set forth without departing from the inventive concept, and right is herein reserved to such other modifications as fall within the scope of the appended claim.

What I claim is:

A cigarette holder comprising a mouth bit having an outer end bore for the insertion of one end of a cigarette therein, said outer end being stepped down and providing a pair of relatively large and small annular shoulders concentric to said bore, a pair of relatively large and small outer and inner perforated shells extending from said bit in spaced apart relation and having open inner ends sleeved onto said large and small shoulders, respectively, and thereby maintained in concentric relation, the outer ends of the shells being closed, and means to connect said outer ends in concentric relation comprising a tubular internally threaded and flanged nut extending axially through said closed ends with the flange innermost, a cap piece opposed to the outer end of the outer shell, a screw extended through said cap piece and threaded into said nut, and a washer on said nut between the outer ends of the shells.

ANTONIO DI RUBBIO.
